UNITED STATES PATENT OFFICE.

WILLIAM WAINWRIGHT, OF SAN FRANCISCO, CALIFORNIA.

SPRINKLER.

SPECIFICATION forming part of Letters Patent No. 357,799, dated February 15, 1887.

Application filed April 26, 1886. Serial No. 200,215. (No model.)

To all whom it may concern:

Be it known that I, WILLIAM WAINWRIGHT, of the city and county of San Francisco, State of California, have invented an Improvement 5 in Sprinklers; and I hereby declare the following to be a full, clear, and exact description of the same.

My invention relates to the class of sprinklers for hose-nozzles; and my invention consists in the combination of devices, all of which 10 I shall hereinafter fully describe.

The object of my invention is to provide a simple and readily-adjustable sprinkler for hose-nozzles.

15 The figure represents a side elevation of a sprinkler embodying my improvement.

A is a hose-nozzle, having the usual tip, a.

B is a collar secured on the top or end of the tip.

20 C is the sprinkling flange or plate. This is made of a fan shape, and is preferably slightly concave on the face which receives the impact of the stream. The flange or plate is secured to the end of the handle or lever D, which is 25 pivoted at d in the arms of the collar B. The lower end of the handle or lever is perforated to receive a threaded stem or guide, E, secured to the nozzle-tip, and a spring, F, bearing against its inner face, holds it outwardly on 30 said guide.

G is a thumb-nut, which engages the outer end of the guide E and bears against the outer face of the lever or handle D, whereby the latter may be forced in against the spring to 35 any desired position.

A small stop, d', on the inner face of the handle is adapted to come in contact with the flange on the nozzle, whereby its inward movement is limited.

40 The stream, emerging from the nozzle-tip, strikes the plate or flange C at a suitable angle, and is thereby broken up and spread out in the form of a spray or sprinkle.

The angle at which the stream meets the plate or flange may be varied by the adjustment of the latter. The limits of this adjustment are determined by setting up the thumb-nut G against the lever or handle D, whereby it is held between said thumb-nut and the spring F. The greater the angle the finer the 45 spray, and vice versa. The plate or flange C may have its angle varied rapidly by means of the thumb of the person operating it pressing upon the lower end of the lever or handle while he is holding the nozzle, and it will be 50 seen that the plate or flange may be thus thrown back at will out of the way, to permit the unobstructed play of the stream.

I am aware that the plate or flange alone, when secured to a nozzle-tip, is not new as a sprinkler. I am also aware that said plate has been 55 pivotally secured in its position and capable of adjustment, whereby its angle may be varied. I therefore do not claim such constructions, broadly, as my invention.

Having thus described my invention, what I claim as new, and desire to secure by Letters Patent, is—

An improved sprinkler, comprising the combination of the hose-nozzle having the tip 70 a, the collar B on said tip, the handle D, pivoted to said collar, having the plate or flange C secured to its upper and a perforation in its lower end, a threaded stem or guide, E, passing through said perforation, a thumb-nut for 75 adjusting said handle, and a spring, F, bearing against the inner face of said handle, all constructed and arranged to operate as herein described.

In witness whereof I have hereunto set my 80 hand.

WILLIAM WAINWRIGHT.
